FLUID PRESSURE DEVICE FOR CLEANING
RIFLED GUN BORES AND CHAMBERS

Marion R. Dyer, Washington, D. C.

Application December 3, 1948, Serial No. 63,422

2 Claims. (Cl. 15—104.2)

(Granted under the act of March 3, 1883, as
amended April 30, 1928; 370 O. G. 757)

1

This invention relates to improvements in tube cleaning apparatus and more particularly to improvements in apparatus for cleaning gun barrels.

One of the problems which has confronted the Navy for the past number of years has been the development of a low cost, rapid, safe and efficient method and apparatus for removing oils, greases or heavy coatings of viscous compounds from the bore (rifling lands and grooves) and chamber (chamber and band slope) surfaces of guns ranging in size from 3"/50 caliber to 16"/50 caliber. These oils, greases or compounds are applied to these surfaces for protection against corrosion and must be removed to return the gun to service.

It was observed in tests leading to the present invention that a good fast solvent for the preservative should not be used since rapid evaporation of the solvent cleans the surface of all protective film and corrosion starts almost immediately after the gun has been cleaned. Accordingly, it was realized that cleaning must be accomplished through the utilization of less volatile fluids, and that improved cleaning implements must be developed.

A tubular mandrel having a longitudinal bore and a plurality of radial brushes spaced apart longitudinally of the mandrel had been proposed by the prior art for cleaning gun barrels by passing a solvent, e. g., steam, through the longitudinal bore and out through radial openings formed in the mandrel between the brushes (cf. U. S. Patent No. 2,367,900). This apparatus while effective in cleaning smooth bores is inefficient in the cleaning of rifled bores because the fluid solvent, e. g., diesel fuel oil, under high pressure is free to escape through the bristles of the brushes leaving the rifling grooves uncleansed. It was discovered that much more rapid and efficient cleaning could be accomplished by sealing off the volume of the bore between the brushes so that the only escape path for the cleaning fluid would be through the rifling grooves.

It is therefore a principal object of the invention to provide a cleaner for gun bores that effectively traps high pressure fluid within the region of the gun bore sealed off by the cleaner thereby directing the high pressure fluid through the rifling grooves as the cleaner is moved longitudinally of the bore.

It is a further object of this invention to provide a cleaner for a gun bore that will effect a rapid and efficient removal of oils, greases

2

or heavy coatings of viscous compounds from the bore surfaces (rifling lands and grooves), the chamber surfaces and the band slope surfaces of guns ranging in size from 3"/50 caliber to 16"/50 caliber.

Other objects and many of the attendant advantages of this invention will be readily appreciated as the same becomes better understood by reference to the following detailed description when considered in connection with the accompanying drawings wherein:

Fig. 1 is an elevational perspective view of the improved cleaner of the invention;

Fig. 2 is a partially sectionalized elevational view; and

Fig. 3 is a cross-sectional view taken on lines 3—3 of Fig. 2.

The cleaning device comprises a mandrel formed of a pipe 3 and rod 28 upon which is supported the central orifice or nozzle head 15. As illustrated, this orifice head is equipped with twelve demountable nozzles 16. These nozzles may be constructed, for example, from $\frac{1}{8}$ " pipe plugs each having a $\frac{1}{16}$ " diameter hole drilled through their respective centers. It is to be noted that the nozzles are constructed in this manner in order to facilitate the cleaning of the interior of the orifice head in the event of its being clogged with foreign matter. Also, with this construction, it is possible to vary the size of the orifice whenever necessary, merely by substituting new pipe plugs with either larger or smaller holes drilled through their respective centers. In the embodiment illustrated six of the demountable nozzles 16a are equally spaced around the circumference of the orifice head 15 at one of its ends, while the remaining six nozzles 16b, although equally spaced around the circumference of the orifice head at its other end, are alternately spaced with respect to the first six nozzles. All of the nozzles are inclined at an angle of 60 degrees with the longitudinal axis of the orifice head in order to secure impingement of the high velocity streams of solvent at the inner edges of the spiral brush assemblies 12 and 19.

As illustrated in Fig. 2 the mandrel consists of the central orifice head 15 which has the pipe 3 and tie rod 28 secured to its opposite ends along its longitudinal axis by threading and/or brazing for example and constitutes a rigid member on which the remaining components of the assembly may be mounted. The pipe 3 serves not only as a member upon which to mount other components, but also functions to direct the

cleaning solvent under pressure into the cavity of the orifice head from whence it is discharged through the demountable nozzles. Assembled on the tie rod 28 adjacent to the orifice head is a brush unit body 18 comprised of a preferably wooden cylinder upon which the spiral bristles 19 are mounted and held in assembled relation by means of the separators 20 and the end clamps 17 and 21. The end clamps 17 and 21 may be held to the body 18 by means of a wood screw 30, for example. These clamps prevent relative rotation of the body and brush assembly.

In order that the end of the cleaning tool supporting the bristle brush 19 may be sealed within the gun bore, there is supported on the rod 28 a flexible stopper 23. This stopper is preferably formed of rubber and is backed up by means of the disc 22 and centering plug 24. The bristle brush unit and the bore sealing stopper assembly are all non-rotatably secured on the tie rod 28 by being held firmly between the face of the orifice head 15, the washer 25, backed up by the clevis 26 and the nut 27. After being tightened this nut 27 may be secured against movement by a cotter pin for example. The clevis bolt 29 serves to secure this end of the cleaner to one end of the cable on a bore-lapping machine.

A second bristle brush unit similar to 13 is mounted on the pipe 3 adjacent the orifice head 15. This bristle brush unit comprises the preferably wooden spiral brush supporting body 11 on which is mounted a spiral brush consisting of the bristles 12 and the separators 13. Mounted on each end of the spiral brush body 11 and secured to it by wood screws 30 are the two assembly clamps 10 and 14. These clamps prevent relative rotation of the brush 12 and body 11.

The bore is sealed off at this end of the cleaner by the rubber stopper 8 held between the retaining disc 9 and centering plug 7 by the clevis 5 and the nut 4. The nipple 1, connected to the pipe 3 by means of a reducing coupling 2, serves as a means for connecting the pipe 3 to the source of high pressure cleaning fluid.

In the operation of the invention for cleaning gun bores the cleaner is connected to one end of a bore-lapping machine cable (not shown) by passing the clevis bolt 6 through the thimble end of the cable. A hose capable of withstanding high pressure as well as deteriorating effects of the fluid solvent is connected to the nipple 1 and source of fluid. This hose is secured to the bore-lapping machine cable for a distance exceeding the length of the gun bore to prevent it from dragging on the bore surface as the cleaning device is reciprocated through the gun by the bore-lapping machine. The other end of the cable of the bore-lapping machine is first passed through the bore of the gun to be cleaned and secured to the cleaner by clevis bolt 6.

It is important that the size of the bristle brushes 12 and 19, and the stopper discs 8 and 23 be selected for the particular size of gun, so that the bristle and stopper or baffle disc snugly fit the bore or land diameter of the gun and that the stopping and reversing position of the cleaner with respect to the muzzle be carefully adjusted.

It was found in cleaning 5"/38 caliber guns that best results were obtained when the bore-lapping machine was adjusted to stop and reverse with the cleaner in the bore and the stopper disc 8 displaced about one-half inch from the muzzle face. The stop adjustment at the other end was set so that approximately one-half the

spiral brush 19 was out of the gun at its breech end.

The snug fit within the bore of the rubber stoppers 8 and 23 is very important since these stoppers cause the fluid solvent to flow by its periphery through the rifling grooves at high velocity. It is this high velocity flow of solvent past the stoppers, coupled with the brushing action of the bristles in contact with a continually changing supply of solvent, that keeps the bristles clean at all times. Moreover, the scraping action of the stoppers aids also in the cleaning operation. The high velocity flow of solvent in its escape past the stoppers not only removes the major portion of the preservative in the rifling grooves, but also removes any preservative that is collected on the leading faces of the stoppers as the cleaner is stroked back and forth through the gun bore. The brushes serve not only to clean the remainder of the compound from the rifling grooves and to complete the cleaning of the lands but also to rotate the device as it passes through the bore. Further cleaning is effected both in the chamber and bore by the washing action of the solvent as it flows from both ends of the gun. Further, as the cleaner begins its stroke, for example, from the muzzle end, the solvent already collected ahead of the disc stopper 23 is given added impetus by the moving cleaner device thus aiding the cleaning of the bore and chamber surfaces by this faster moving flow of solvent. It should also be noted that the solvent escapes with high velocity past both disc stoppers 8 and 23 and therefore bore cleaning is effected simultaneously at each stopper regardless of the direction of travel of said cleaning device. It is also believed that the turbulent solvent entrapped in the chamber between the stoppers 8 and 23 not only materially serves to keep the brushes clean, but also aids in the cleaning of the bore surfaces. The turbulence is achieved by the arrangement of the nozzles 16a and 16b in the orifice head 15.

The gun chamber is of a diameter larger than the bore, but is effectively cleaned, nevertheless, by the method and device described herein. It is believed the sudden release of the high pressure solvent entrapped between the stoppers 8 and 23 at the instant the leading stopper (23) enters the larger chamber effectively contributes to the cleaning of the chamber. Further cleaning of the chamber is of course achieved by the arrangement of nozzles producing the high velocity streams of solvent in a direction having a component along the axis of the bore.

Obviously many modifications and variations of the present invention are possible in the light of the above teachings. It is therefore to be understood that within the scope of the appended claims the invention may be practiced otherwise than as specifically described.

The invention herein described may be manufactured and used by and for the Government of the United States of America for governmental purposes without the payment of any royalties thereon or therefor.

I claim:

1. A cleaning device for use with fluid cleaning solvent to remove anti-corrosive materials from rifled gun bores and adapted to be moved axially in the bore comprising a central orifice head, a tubular support for said head extending on opposite sides thereof to form a fluid passage to said head, first and second spiral brushes mounted on said support one on each side of said head,

flexible stopper means having a diameter slightly in excess of the land diameter of said bore secured to said support one on the side of each brush opposite said head, two sets of nozzles on said head in fluid communication with said tubular member, said nozzles being generally radially disposed, one set of nozzles being axially inclined in the direction of the first brush, and the other set of nozzles being axially inclined in the direction of the second brush whereby a high velocity discharge of fluid cleaning solvent entrapped between said flexible stopper means will be effected at the rifle grooves when said fluid is applied from a high pressure source to said head and nozzles through said tubular member.

2. A cleaning device for use with fluid cleaning solvent to remove anti-corrosive materials from rifled gun bores and adapted to be moved axially in the bore comprising a central orifice head, a tubular support for said head extending on opposite sides thereof to form a fluid passage to said head, a pair of spiral brushes mounted on said support one on each side of said head, flexible stopper means having a diameter slightly in excess of the land diameter of said bore secured to said support one on the side of each brush opposite said head; at least two sets of nozzles on said head in fluid communication with said tubu-

lar member, each set including a plurality of nozzles circumferentially spaced about the head, said nozzles being generally radially disposed with one set being axially inclined in the direction of one brush and another set being so disposed with relation to the other brush, whereby a high velocity discharge of fluid cleaning solvent entrapped between said flexible stopper means will be effected at the rifle grooves when said fluid is applied from a high pressure source to said head and nozzles through said tubular member.
